UNITED STATES PATENT OFFICE

2,110,299

BOTTLE RACK

Cecil Edward Hinkle, Oklahoma City, Okla.

Application November 23, 1936, Serial No. 112,355

1 Claim. (Cl. 211—74)

The present invention relates to a bottle rack and the object of the invention is to provide means whereby bottles may be stored in a convenient and accessible manner and being readily 5 releasable from the rack.

With the above and numerous other objects in view as will appear as the description proceeds, the invention consists in certain novel features of construction, and in the combination and arrangement of parts as will be hereinafter more 10 fully described and claimed.

In the drawings:—

Figure 1 is a top plan view of the rack embodying the features of my invention.
15 Figure 2 is a sectional view taken substantially on the line 2—2 of Figure 1.

Figure 3 is a bottom plan view of another embodiment of the invention.

Figure 4 is a vertical sectional view there-
20 through.

Figure 5 is a perspective view of one of the slides.

Referring to the drawings in detail it will be seen that numerals 5 denote end members in 25 which are fixed side members 6—6 and partition members 6'. In between a pair of side members or partition members 6 and 6' are track members 7 arranged in pairs and the pairs are provided on inner sides with grooves 8. Guide members 30 9 are provided on their sides with tongues 10 slideable in the grooves. The underside of each member 9 is formed with a longitudinally extending groove 9'. Springs 11 are seated in the grooves 9' and are connected at one end to the members 9 35 and connected at their opposite ends to one of the members 5. In this way it will be seen that in the rack the bottles 20 are naturally urged to one end of the rack structure. As shown in the 40 drawings the left hand end of the members 9

are provided with uprights 21 and on the upper ends thereof as at 22 members for engaging the bottles.

It is thought that the construction, operation, utility and advantages of this invention will now 5 be quite apparent to those skilled in this art without a more detailed description thereof.

The present embodiment of the invention has been described in considerable detail merely for the purposes of exemplification since in actual 10 practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention what is 20 claimed as new is:—

A rack of the class described comprising a trackway including a pair of spaced parallel bottom rails having guide channels in their opposed sides, a slide member flush with the surfaces of 25 the rails and having tongues fitted in said channels, a groove in the under side of the slide member, spring means extending longitudinally between the rails and seated in said groove of the slide member, said spring having one end 30 attached to the under side of the slide member for urging the same in one direction, an L-shaped member having its base secured to the upper surface of the slide member adapted to underly a bottle positioned on the slide member and 35 an arcuate horizontal block secured to the upper end of said L-shaped member for engaging and moving the bottle during movement of the slide member.

CECIL EDWARD HINKLE. 40
